Louis H. Bannister.

UNITED STATES PATENT OFFICE.

LOUIS H. BANNISTER, OF PASADENA, CALIFORNIA.

CASKET-HANDLE.

SPECIFICATION forming part of Letters Patent No. 498,610, dated May 30, 1893.

Application filed July 1, 1892. Serial No. 438,666. (No model.)

To all whom it may concern:

Be it known that I, LOUIS H. BANNISTER, a citizen of the United States, and a resident of the city of Pasadena, county of Los Angeles, and State of California, have invented a new and useful Improvement in Burial-Casket Handles; and I do hereby declare that the following is a full, clear, and exact description of the same, reference being had to the drawings accompanying this specification.

Heretofore it has been the custom of undertakers to secure the lifting handles to the sides of caskets as inseparable fixtures, and to bury the same with the casket.

My invention consists of a device for quickly attaching to, and detaching the handles from caskets; the purpose being to have more elaborate handles than are commonly used, and to detach the same just before the interment or cremation.

The invention consists in the following construction and arrangement:

In the drawings, Figure 1 is a vertical view showing one of the several posts through which the extended rail or tube forming the handle passes. Fig. 2 is a vertical section of Fig. 1. Fig. 3 shows another mode of construction, in which the fastening device is placed between the posts through which the rail or tube forming the handle passes. Fig. 4 is a bottom view reduced in size. Fig. 5 is a plan of the plate to be fastened to the side of the casket, and to which the handle is attached. Fig. 6 is an end view of the bolt, and Fig. 7 an edge view of the attachment plate.

The device complete consists of several posts similar to that shown in Fig. 1 and through which the rod or tube forming the handle passes.

In the sectional view, Fig. 2, is shown one of the posts and attachments, consisting of the plate *s* to be screwed or otherwise fastened to the side of the casket *w*; the base *g* around which is the rim *n x*; the post *D*; the thumb nut *a*; the bolt *o* with the head *c* and square neck *r*; and a portion of the rail *b*. The bolthead engaging with the plate *s*, the bolt passing through the axis of the hollow post *D*, and diametrically through the rail handle *b*, and the end of the bolt provided

with a screw engaging with the thumbnut *a*, form the fastening device.

The plate *s*, as seen in Fig. 7, is made from a piece of sheet metal, the end portions from *z z* forming the base. The offset from *z z* to *y y*, is made by folding the metal at *y y* and *z z*, the swell being made to admit the bolt-head which rests in the opening thus formed.

In the front view, Fig. 5, the rectangular opening *m* is shown. This opening is made a proper width to admit the bolt, the head of said bolt projecting to either side sufficiently to be held securely against the under side of the plate. At *i i*, depressions are made in the plate, to prevent any slipping of the bolt-head when contained therein.

In Fig. 4 the plate *s* is shown in dotted lines, and the bolt engaged therewith.

The attachment plate *s* may be made in many different ways but the one I prefer is the one described in this specification and shown in the accompanying drawings.

The plate *s* projecting from the surface line of the casket *ff*, a corresponding offset is made in the base *g* from *n n* to *x x*, thus bringing the lower edge of the base *x x* to the surface of the casket, in line *ff*, as plainly seen in Fig. 2. In the same figure the bolt *o* is made square at the neck *r*, and the vertical hole through the base through which the bolt passes is also square. The bolt has free end motion, the neck *r* being square to prevent the bolt from turning on its axis when tightening or loosening the thumbnut *a*. In some cases I have a coiled spring around the bolt *o*, one end of the coil being fastened to the bolt *o* below the rail *b*, the other end fastened to the base near the neck *r*, said spring being for the purpose of projecting the bolt-head *c* when the thumbnut *a* is loosened, the object being to make easier the connection with the plate *s*.

In Fig. 3 are represented three posts on one base, the rail forming the handle passing through the outer posts *D D*, the central or middle post being shorter, and containing the attachment device as heretofore described. In this figure the base is made sectional, showing in dotted lines the attachment device.

To use the device, fasten in horizontal line as many plates to each side of the casket, as

there are connecting devices in the handles, the distance between the plates corresponding with the distance between the boltheads, said plates being so placed that the openings 5. *m* will all look in the same direction. To attach the handles, loosen the thumbnuts *a* sufficiently to allow the boltheads to pass under the swell in the plates *s* and the necks of the bolts into the openings *m*; when in place 10 turn each thumbnut *a* until the posts are rigid. To detach the handles, loosen the thumbnuts *a*, and slide in the opposite direction.

Having described my invention, what I 15 claim as new, and desire to secure by Letters Patent, is—

1. A detachable casket handle comprising

a handpiece and support provided with a bolt and thumbnut adapted to be secured to a plate that is permanently fastened to the side 20 of a casket, substantially as described.

2. In a burial casket handle, the combination with the plate *s*, the bolt *o* and bolthead *c*, the thumbnut *a*, the rail *b*, the post *D*, provided with the rim *n* *x* around the base *g*, 25 substantially as described.

In witness whereof I have hereunto signed my name in the presence of two subscribing witnesses.

LOUIS H. BANNISTER.
